R. S. BLAIR

STEEL BARREL

Filed Jan. 9, 1919

Robert S. Blair Inventor

UNITED STATES PATENT OFFICE.

ROBERT S. BLAIR, OF SOUTH ORANGE, NEW JERSEY, ASSIGNOR TO MEURER STEEL BARREL COMPANY, INC., A CORPORATION OF NEW YORK.

STEEL BARREL.

Application filed January 9, 1919. Serial No. 270,353.

To all whom it may concern:

Be it known that I, ROBERT S. BLAIR, a citizen of the United States, and a resident of South Orange, in the county of Essex and 5 State of New Jersey, have invented an Improvement in Steel Barrels, of which the following is a specification.

This invention relates to the construction of steel barrels and the like, and with regard to its more specific aspects, to the end or chime joint portions thereof. One of the objects of this invention is to provide a construction of the above type which shall possess strength and security in a high 15 degree and shall be economical in the use of metal. Another object is to produce a durable construction of the above type, which can be quickly and conveniently made. Another object is to provide a simple and 20 practical construction of the above type not dependent upon solder or holding means and which shall nevertheless be thoroughly fire-proof. Other objects will be in part obvious and in part pointed out hereinafter. 25 The invention accordingly consists in the features of construction, combinations of elements and arrangement of parts which will be exemplified in the structure herein-after described and the scope of the application of which will be indicated in the following claims.

In the accompanying drawing in which are shown one or more of various possible embodiments of the several features of this 35 invention,

Figure 1 is a sectional view through the end or chime joint of a steel barrel;

Figure 2 is a similar view of a modified construction.

Similar reference characters refer to similar parts throughout both views of the drawing.

Referring now to Figure 1 of the drawing, there is shown at 10 a portion of the 45 shell or body of the barrel, the same being formed of sheet metal of suitable thickness in any desired manner.

Within the end of this shell is tightly fitted a head 11 also formed of sheet steel 50 provided with a flange 12 which preferably rests snugly within and against the end of the body 10.

The parts being thus assembled, it being understood that both ends of the barrel may 55 be of identical construction, the edges of

both flange 12 and body 10 are then rolled into the interlocking double seam joint shown at 13. The parts of the respective members are readily traced in the sectional view appearing on the drawing. 60

A chime ring preferably formed of malleable steel of annular conformation is given the cross section indicated at 14 except that the outer free edge 15 extends substantially as indicated in dotted lines. The inner 65 flange of the ring 14 is given a curved conformation to provide a concave surface at 16 and to extend upwardly and rest against the under surface of the barrel head as at 17. 70

The ring or hoop provided as above is thus forced within the flange or chime of the barrel, it being understood that the seam or joint 13 may be originally formed in such manner that its inner surface lies in 75 the plane of the line 18. With the ring in position, the joint or seam 13 is rolled or spun inwardly to fit snugly within the concave surface of the inner flange of the hoop, the latter thus extending over and interlocking with the shoulder formed at 19. The outer flange 15 is bent upwardly and inwardly so as to enter and interlock with the outer surface of the joint. This outer surface will in general be of a concave form, 80 due to forcing the seam in the concave surface 16 of the ring or hoop. 85

The lower surface of the hoop is preferably so formed as to provide a bearing surface at 20 which will be substantially beneath the lower end of the joint. All shocks are thus transmitted directly upwardly to the wall of the barrel without a marked tendency to displace the parts. 90

The head 11 at least, including its flange, 95 is preferably galvanized on both surfaces in order that the exposed portions of the shoulder at 21 be protected as fully as possible.

It is also to be noted that the chime ring should fit the end of the inner joint closely as at 22. Furthermore, the outer surface of the joint where engaged by the outer flange of the ring, and the opposite surface of engagement between the inner surface of 100 the joint and the inner flange of the ring, should be non-divergent in a direction away from the end of the joint, that is, in this case, an upward direction. The barrel is 105 subjected to heavy shocks which fall upon 110

this ring and tend to drive it upwardly, and if these surfaces diverge in an upward direction, there is a tendency for it to wedge the outer flange of the ring into a loose relation 5 with the inner joint.

It will be seen that in the use of a barrel constructed as above, the inner joint is clamped between the flanges of the chime hoop and that both of these flanges interlock to a certain extent with the respective 10 surfaces of the joint. This is brought about moreover without the outer flange extending over the outer shoulder at 21 although the inner flange extends over the inner shoulder. 15 The flanges of the chime are of such nature as to present great strength and the inner seam is formed under such pressure that the metal surfaces are tightly united. If desired, some form of plastic cement may be 20 employed to care for isolated leaks due to defects of material or workmanship, but no solder is required and accordingly the barrels are thoroughly fireproof.

In Figure 2 of the drawings is shown a 25 different form of joint in which the body of the barrel shown at 23 is provided with a head 24 flanged at 25 as in the construction first described. The edges of the head, flange and body are rolled into a double 30 seam joint 26, also as first described. The heavy malleable chime hoop 27, however, is provided with its inner flange adapted to substantially rest against the head as at 28 and is shaped to have on the outer surface 35 of its inner flange, a number of corrugations 29. The outer flange 30 prior to the formation of the barrel, rests substantially as indicated in dotted lines. The chime hoop being placed in position, the double seam is 40 rolled into interlocking relation with the corrugations 29. If desired, these corrugations may be rolled into the double seam before the parts are assembled and may be either in parallel form or may form a thread 45 to co-act with a similar thread formed by the corrugations 29. The mechanical features of the joint are completed by rolling the flange 30 into the position indicated in full lines and thereupon the entire barrel 50 may be galvanized to perform the functions set forth in connection with the construction shown in Figure 1.

Although both of these arrangements possess features in common and advantages peculiar to themselves, the construction first described forms the subject matter of the most specific claims of this application.

It will thus be seen that there is provided a 60 barrel construction of a strong and secure nature in which the objects of this invention are achieved and that such a construction is well adapted to meet the severe conditions of hard practical use.

As various possible embodiments might 65 be made of the above invention and as va-

rious changes might be made in the embodiments above set forth, it is to be understood that all matter herein set forth or shown in the accompanying drawings is to be interpreted as illustrative and not in a limiting 70 sense.

I claim as my invention:

1. In construction for steel barrels and the like, in combination, a body portion, a flanged head portion fitted therein, the edges 75 of said body and flange of said head being formed into a joint of at least four thicknesses of metal, and a heavy annular malleable ring provided with a pair of flanges embracing said joint, the outer surface of said joint being of concave form and the outer flange of said ring being forced into the concavity formed thereby.

2. In construction for steel barrels and the like, in combination, a body portion, a flanged head portion fitted therein, the edges 80 of said body and flange of said head being formed into a double seam joint of at least four thicknesses of metal, and a heavy malleable annular ring provided with a pair 85 of flanges embracing said joint, the outer of said flanges interlocking with said joint on its outer lateral surface.

3. In construction for steel barrels and the like, in combination, a body portion, 90 a flanged head portion fitted therein, the edges of said body and flange of said head being formed into a joint of at least four thicknesses of metal, and a heavy malleable ring embracing said joint, said joint being 95 deformed throughout the circumference of the barrel and said ring interlocking with the deformity formed therein.

4. In construction for steel barrels and the like, in combination, a body portion, a flanged head portion fitted therein, the edges 100 of said body and flange of said head being formed into a joint of at least four thicknesses of metal, and a heavy malleable annular ring embracing said joint, the inner 105 surface of said joint engaged by said ring being of convex form and the outer surface thereof being concave.

5. In construction for steel barrels and the like, in combination, a body portion formed of sheet metal, a flanged head portion formed of sheet metal and having the flange fitted within the end of said body portion, the edges of said flange and said body portion being rolled into a double seam 110 joint of at least four thicknesses of metal and said double seam joint being formed to provide a recess at the joint, and a heavy malleable ring embracing said joint and extending into said recess to interlock therewith.

6. In construction for steel barrels and the like, in combination, a body portion formed of sheet steel, a head portion formed 115 of sheet steel and having a flange fitted 120

within the end of said body portion, the edges of said flange and said body portion being rolled into an inner joint of at least four thicknesses of metal and forming a shoulder on the outer surface of the joint, and a heavy malleable member fitted within said flange and provided with a portion fitting closely about the end of said joint and thence extending over the outer side of said joint and free from interlocking relation with said shoulder, the inner and outer surfaces of said joint gripped by said malleable member being non-divergent in a direction away from the end of the joint, and the outer surface of said joint being outwardly concave where it is gripped by said malleable member.

7. In construction for steel barrels and

the like, in combination, a body portion formed of sheet metal, a flanged head portion formed of sheet metal and having a flange fitted within the end of said body portion, the edges of said flange and said body portion being rolled into a double seam joint of at least four thicknesses of metal and said double seam joint being formed to provide a recess at the joint, and a heavy malleable ring embracing said joint and extending into said recess to interlock therewith, said recess being extended continuously about the barrel.

In testimony whereof, I have signed my name to this specification this 3rd day of January, 1919.

ROBERT S. BLAIR.
